UNITED STATES PATENT OFFICE

WARREN STANDISH MILLER, OF SOUTH ST. PAUL, MINNESOTA

DESIGN FOR A SAFETY RAZOR BLADE SHARPENER

Application filed November 9, 1932. Serial No. 45,849. Term of patent 3½ years.

To all whom it may concern:

Be it known that I, WARREN STANDISH MILLER, a citizen of the United States, residing at 241 Fifth Avenue North, South St. Paul, in the county of Dakota and State of Minnesota, have invented a new, original, and ornamental Design for a Safety Razor Blade Sharpener, of which the following is a specification, reference being had to the ac-

companying drawing, forming part thereof.

Fig. 1 is a top plan view of a safety razor blade sharpener, showing my new design.

Fig. 2 is a bottom view, and

Fig. 3 is an end view thereof.

I claim:

The ornamental design for a safety razor blade sharpener as shown.

WARREN STANDISH MILLER.
